Fig. 5

Fig. 6

Fig. 7

Fig. 8

FIG. 1 is a perspective view of an egg carton showing my new design;

FIG. 2 is a partial top plan view thereof of the left portion of FIG. 1;

FIG. 3 is a partial top plan view of the right portion of the egg carton of FIG. 1 wherein the bottom of the egg pockets comprise several concentric rings;

FIG. 4 is a side elevational view of the egg carton shown in FIG. 1;

FIG. 5 is an end elevational view of the egg carton shown in FIG. 1;

FIG. 6 is a fragmentary sectional view of the egg carton as viewed along lines 6—6 of FIG. 2;

FIG. 7 is a fragmentary sectional view of the egg carton as viewed along lines 7—7 of FIG. 3; and

FIG. 8 is an end sectional view of the egg carton as viewed along lines 8—8 of FIG. 2.

I claim:

The ornamental design for an egg carton, as shown and described.
